UNITED STATES PATENT OFFICE.

JOSIAH HARPUR SYDNEY MAY, OF BELFAST, IRELAND.

ADJUSTABLE EASY-CHAIR OR LOUNGE.

SPECIFICATION forming part of Letters Patent No. 639,076, dated December 12, 1899.

Application filed March 8, 1899. Serial No. 708,268. (No model.)

To all whom it may concern:

Be it known that I, JOSIAH HARPUR SYDNEY MAY, manufacturer, a subject of the Queen of Great Britain and Ireland, residing at 2 Stranmillis Park, in the city of Belfast, in the county of Antrim, Ireland, have invented certain new and useful Improvements in Easy-Chairs or Lounges, (for which I have applied for Letters Patent of Great Britain and Ireland, dated September 16, 1898, and numbered 19,652;) and I do hereby declare the following to be a full, clear, and exact description of my invention, such as will enable others skilled in the art to which it appertains to make and use the same, reference being had to the accompanying drawings, and to the letters of reference marked thereon, which form a part of this specification.

My invention relates to chairs and lounges for sitting or reclining upon; and it consists, substantially, in such features of construction, arrangement, and combinations of parts as will hereinafter be more particularly described.

25 The primary object of my invention is to provide means for the support of the human body evenly from head to heels when sitting or reclining by the adjustment of the chair or lounge to various positions of the head, trunk, thighs, and legs independently, and to consequent changes of the posture of those parts of the body at the will of the person using the article, whereby comfort and rest are promoted.

35 In the accompanying drawings, Figure I is a vertical longitudinal section of a chair made in accordance with my invention. Fig. II is a front view, partly in section, the upholstering being removed, both leg-rests and one 40 thigh-rest being entirely omitted and part of the other thigh-rest being also omitted. Fig. III is a front view, on an enlarged scale, of one thigh and one leg rest detached. Figs. IV, V, VI, VII, VIII, and IX are views of detached 45 details on an enlarged scale.

The frame of the chair is indicated by the letters A A, representing the sides, and a a uprights between the front and back thereof, connected by the cross-rails C, C', C², C³, and 50 C⁴, the rail marked C secured at either end to an upright a and forming a bottom for the shallow fixed seat. The sides of the back B

are connected at base and top by the cross-bars B² and B³, and the cross bar or slab B² is connected at each end to the adjacent upright a by a link B', screwed or bolted at one end to it and pivoted at the other to such side at a point in front of the back and some distance above the seat. This latter pivot may be formed by passing a pin through two metal plates m, bolted to each side of the upright bar a. The sides of the back-rest frame may be strengthened by side stays B⁴, and, if desired, an additional cross-bar B⁵ may be employed for tacking the cover to. By placing 65 the pivot in the position indicated I center the back-rest, so that the head-rest, herein-after described, will always be in the same relative position to the head of the person occupying the chair, whatever may be the inclination of the back-rest.

Underneath the back edge of the bar or slab B², I hinge a rack R, the other end of which passes through a slot in the vertical bar O, fixed to the cross-rail C and C'. A 75 bolt or pin b across the slot in this vertical bar O engages a notch in the rack R and holds the back-rest firmly in any required position. When a change of posture is desired, the rack R may be unlocked by the aid 80 of a cord or chain c, attached to the free end thereof, and a spring S on each side of the chair attached at one end to a pin between the plates m above and behind the pivot in such plate on which the link B' centers and 85 at the other end to a pin at the opposite extremity of the link B'. Thus the person occupying the chair by pulling the cord or chain attached to the rack R may disengage the rack, and while so disengaged with the aid of 90 or controlling the springs S alter the inclination of the back-rest at pleasure, and by again dropping the rack upon a bolt or pin b secure it when the desired position has been arrived at.

The head-rest surmounting the back-rest 95 consists of a frame H, H', H', and H², of which the sides H' H' may be in an elliptical form.

For adjusting the inclination of the head-rest I attach it to the sides of the back-rest B by two internal metal strips h h, fastened 100 within the sides H' H' and pivoted at their lower ends to the sides of the back-rest B at i i a little below the cross-bar B³, so that the whole head-rest may move on a center out-

side it and give even support to the back of the head in all positions.

In order to keep the metal strips h clear of the stuffing of the back-rest, I inclose the 5 lower portion of each such strip h with a triangular casing K , fastened within the side of the back-rest B . If it be desired to keep the head-rest of the full width of such back-rest, I introduce blocks of wood between the metal 10 strips h and the sides $H' H'$, as shown.

The arrangement for adjusting and locking the inclinations of the other parts of the chair by dropping a rack upon a bolt or pin is unsuitable to the head-rest. The special 15 means which I employ in the latter case are more fully illustrated in Figs. VI, VII, and VIII. For these purposes I fix a block of wood W on the top rail B^3 of the back-rest B , and to this block W , I attach a latch Y by 20 a pivot at or near to its center and preferably guided by a slotted metal plate w on the end of the block W , and to the lower rail H^2 of the head-rest I attach a flanged rack or plate X , as shown in Fig. VII, notched on the 25 upper side and standing out at right angles from the rail H^2 , so as to cross the latch Y near to the slotted metal plate w at the end of the block W . I provide the free end of the rack or plate X with a projection or stop 30 to prevent its passing beyond the range of the latch so as to allow the head-rest to move too far forward.

To operate the latch Y , I form the end farthest from the rack or plate X , as shown in 35 Fig. VIII, with a bend, and I pass a small spring-wire y through holes in that end and through the lower extremity of a small spiral spring Z , which is suspended from the top of the cross-bar B^3 and has attached to its lower 40 extremity a cord or chain z' , passing down within the side B of the back-rest through a small pulley on the cross-rail C' up to the arm of the chair. When the cord is pulled, with the head still leaning upon the head-rest, 45 the spring-wire y will be bent, and when the head is lifted the latch Y will be disengaged by it from the rack or plate X to enable the head-rest to be adjusted. When the cord is again released, the spring Z will restore the 50 latch Y to one of the notches in the rack or plate X . A spring S' at the back of the head-rest presses against the flange x of the rack or plate X and the top bar B^3 of the back-rest, so as to force the head-rest forward. 55 This spring may be kept in position by any ordinary-well-known means usually employed for such a purpose.

The supports for each thigh and leg of the user are separate and independently adjustable. The whole framework supporting each thigh and leg is attached by a hinge or pivot p to flanges at the ends of a horizontal T-shaped plate t , which is fixed to the top of a vertical pivot P , capable of turning horizontally in borings in the cross-rails $C C'$. The plate t is stayed by a wooden strut t' , bolted at b' , its lower end to the vertical pivot P .

The thigh-rest turns vertically on the pivot p on the flanges of the plate t and having its bearings on the flanges of a metal plate t^2 , 70 fastened internally to the sides $T T$, which may be connected by a cross-rail t^3 behind the pivot p . The plate t^2 also serves to prevent the thigh-rest from deviating from its rectangular form. A spring S^2 , having a 75 straight prolongation at each end, one of which bears against the internal metal plate t^2 , while the other passes through the plate t , encircles the pivot p and raises the thigh-rest and the parts connected therewith when desired. A light cross-rail t^4 between the sides $T T$ at their other ends will carry the upholstery at that end.

To support the thigh and leg rests, I construct a frame of an inverted pyramidal form 85 underneath the thigh-rest. This frame consists at the back of a metal strap v , bent double, with the legs diverging and secured at the upper ends, respectively, between the thigh-rest side T and the internal metal plate t^2 by 90 a pin or screw passing through them. The front of the frame is a tapered board or plate V , the edges of which may be of any desired form, but preferably lying between the sides $T T$ of the thigh-rest and having shoulders 95 passing beneath and to the outer edge of such sides $T T$. A recess or perforation in the back of the board or plate V receives the bend of the metal strap v , and within this bend I place the fixed end of the rack R' , the pivot of which, 100 e , passing through the board or plate V , secures both the bend of the metal strap and the fixed end of the rack in position. The free end of the rack R' moves in a slot in the vertical pivot P , in which a pin b' engages 105 one of the notches of the rack, and thereby locks the thigh-rest T in any desired position, while a stud at that end prevents the rack from passing out of such slot. A cord or chain and spring are attached to the free end 110 of the rack R' for unlocking it in like manner, as before described in connection with the rack R .

The leg-rest $L L$ consists of a rectangular frame swung upon a bar or pivot d below the 115 center thereof and working in bearings carried by a plate of metal g , turned up at each end and having the turned-up portions extended like arms $g' g'$ and reaching to the sides $T T$ of the thigh-rest. The upper ends of 120 such arms $g' g'$ turn on pins or studs in the center of the outer ends of the thigh-rest sides $T T$ and preferably pass through small metal plates screwed to the inner sides thereof below the cross-bar t^4 . At the lower end of the 125 plate g two perforated projections $g^2 g^2$ provide bearings to carry the bar or pivot d , on which as a center a metal plate $j j$ and the leg-rest swing, the metal plate $j j$ being furnished with bent ends screwed to the leg-rest 130 sides $L L$ internally. The top of the leg-rest should at all inclinations be capable of passing clear of the cross-rail t^4 of the thigh-rest. Below the metal plate g are two other pro-

jections g^3 g^4 , carrying a pin e' , on which two small metal plates r^2 r^2 turn and between the outer ends of these plates r^2 r^2 the rack R^2 for locking the leg-rest in position is secured 5 by a bolt at the end and two small screws in the middle, providing an open space at that end of the rack R^2 for the passage of the lever l by which the leg-rest is raised vertically. The free end of the rack R^2 moves in 10 a slot in the lower end of the board or plate V and locks the position of the leg-rest by engagement with the pin b^2 and is unlocked by the aid of a cord or chain and spring in the same manner as the back and thigh rest 15 racks R and R' . It also is provided with a stud to prevent its passing out of such slot. Thus the leg-rest, in addition to its horizontal motion with the thigh-rest, has two independent motions—one vertically around the 20 end of the thigh-rest and locked by the rack R^2 and the other a free swing on the bar or pivot d . The upper end of the lever l passes through a slot near the top of the board or plate V and turns on a pin in this slot. From its 25 short end beyond the pin depends a spring S^3 , which is secured at its opposite extremity by a pin fixed in the lower slot of the board or plate V a little above the rack R^2 , and the back of the board or plate V is recessed to 30 receive such spring. The lower end of the lever l travels on a roller carried by the pin e' between the plates r^2 r^2 .

The arrangement which I have described of the lever l and the spring S^3 , besides obviating the difficulty of placing a spring in any other position to raise the leg-rest, will give it a greater leverage when it is shorter and at the same time (the leg-rest being higher) has more work to do. To give the greatest 35 benefit, the upper end of the spring should be bent to one side and the short end of the lever should be bent up as much as possible to bring the fulcrum of the lever and the two points of application of the spring as nearly 40 in a line as practicable without pressing the side of the spring against the lever when the leg-rest is at the lowest position.

For the purpose of supporting the heel when necessary I provide a slide f , Fig. I, 50 which passes through recesses in the lower cross-rail of the leg-rest and between the plate j and the bar or pivot d , small blocks of wood, screwed underneath the plate j , acting as guides. A ring may be attached to the 55 upper part of the slide to enable the person in the chair to move it up or down.

The notches in the racks R , R' , and R^2 and the plate X are cut so as to hold against the pressure of the back, thigh, leg, or head in 60 one direction and the springs S , S^2 , S^3 , and S' , respectively, in the other directions and should be made an easy fit for the pins.

Near the lower ends of the cords c , c' , and c^2 , attached to the racks R , R' , and R^2 for the purpose of disengaging them, as described, I introduce a spiral spring s , (see Fig. IX,) in each case fastened at its opposite ends to points in

the cords sufficiently apart from each other to allow the spring to be stretched without overstraining it. By this arrangement it is 70 only when the pressure of the part of the sitter upon the appropriate rest is being lifted off that the rack becomes disengaged and the spring S , S^2 , or S^3 begins to operate.

The chair may be upholstered according to 75 taste and with or without springs in the back and seat.

The lines U U U U suggest the shape of the middle of each part when upholstered.

Without limiting myself to the precise details of construction and arrangement of the parts described and shown, I claim—

1. In a chair, the combination with the seat, of a back, a head-rest and a thigh and leg support, each independently pivoted, and 85 each provided with means to lock it in adjusted position, and with a spring normally tending to move it in direction opposite to that in which it tends to move under the weight of the occupant of the chair, substantially as set forth.

2. In a chair, the combination of a vertical pivot P , a flanged plate t connected to the pivot to turn therewith, a thigh-rest pivoted to the flanged plate to have vertical swinging movement thereon, a leg-rest hinged to the thigh-rest to have independent vertical movement, racks to lock the thigh-rest and leg-rest independently in adjusted position, and springs acting on the thigh-rest and leg-rest 100 independently and normally tending to swing them upwardly, substantially as described.

3. In a chair, a thigh-rest supported to swing vertically and horizontally, a frame connected to the outer end of the thigh-rest to swing 105 horizontally therewith, and to have an independent vertical swinging movement, a leg-rest pivoted intermediate its ends in said frame to have a rocking movement independently of the frame, a rack to lock the frame 110 and leg-rest in adjusted position, a pivoted lever l engaging the frame at one end, and a spring S^3 connected at one end to the other end of the lever, and at its other end to a fixed support, substantially as and for the purpose 115 set forth.

4. In a chair, the combination of a thigh-rest, a pyramidal frame secured to its under side, a rack connected to the lower end of the frame, a locking-pin for the rack, a leg-rest 120 having a hinge connection with the thigh-rest, a rack connected to the leg-rest, a pin in the frame to be engaged by the last-named rack, a lever pivoted in the frame and engaging with one end of the leg-rest, and a spring connected at one end to the other end of the lever, and at its other end to said frame, substantially as set forth.

5. The combination with a thigh-rest, of a plate g having arms g' g' pivoted to the sides 130 of the thigh-rest, a bar d supported in bearings on said plate, and a leg-rest pivoted intermediate its ends on the said bar, substantially as set forth.

6. In a chair, the combination of the frame and fixed seat, of an inclined back having a cross-bar at its lower end, links connecting said bar and the sides of the frame to permit the inclination of the back to be changed, a rack hinged to the bar and engaging a pin on the frame, and a spring connected at one end to the side of the frame and at its other end to said bar, and normally tending to decrease the inclination of the back, substantially as set forth.

7. In a chair, the combination with an adjustable back-rest, of a head-rest provided with depending strips *h* pivoted at their lower ends to the sides of the back-rest, casings enclosing said strips at their lower ends, a forwardly-projecting block on the upper end of the back-rest, a latch pivoted thereon and lying parallel to the back-rest, a notched plate secured to the lower end of the head-rest and extending transversely across the

latch to be engaged thereby, a spring interposed between the lower end of the head-rest and the upper end of the back-rest and tending normally to separate them, and means to disengage the latch from the notched plate, substantially as set forth. 25

8. In a chair, the combination with a fixed pin and an adjustable part of said chair, of a rack hinged at one end to the adjustable part and adapted to engage the said pin, a cord connected to the rack and operative to lift it out of engagement with the pin, and a spring interposed in said cord, substantially as and for the purpose set forth. 30

In testimony whereof I have signed my name to this specification in the presence of two subscribing witnesses.
